UNITED STATES PATENT OFFICE.

LEWIS B. JEFFCOTT, OF NEW YORK, N. Y.

CONVERTIBLE BED AND MATTRESS THEREFOR.

No. 926,421.

Specification of Letters Patent.

Patented June 29, 1909.

Application filed November 21, 1908. Serial No. 463,756.

To all whom it may concern:

Be it known that I, LEWIS B. JEFFCOTT, a citizen of the United States, and a resident of the city of New York, borough of Manhattan, 5 in the county and State of New York, have invented a new and Improved Convertible Bed and Mattress Therefor, of which the following is a full, clear, and exact description.

The object of the invention is to provide a 10 new and improved convertible bed and mattress therefor, arranged to permit of conveniently converting the bed to form a davenport, a single bed, a double bed or a couch, the mattress conforming to the changes, thus 15 requiring no separate mattresses for the different forms in which the bed is used.

For the purpose mentioned the bed consists of a main section and hinged side or extension sections, and the mattress consists of 20 a main section and extension sections hingedly connected with each other, and one being hingedly connected with one side of the main section to allow of extending or folding the mattress sections to fit the bed sections in 25 their respective positions.

A practical embodiment of the invention is represented in the accompanying drawings forming a part of this specification, in which similar characters of reference indicate corresponding parts in all the views.

Figure 1 is a perspective view of the improvement, showing the parts arranged in the form of a davenport; Fig. 2 is a cross section of the improvement showing the parts 35 arranged as a single bed; Fig. 3 is a similar view of the same, showing the parts arranged as a couch; Fig. 4 is a like view of the same, showing the parts arranged as a double bed; and Fig. 5 is a perspective view of the bed 40 and showing the sections swung up to give access to the receptacle for holding the bed clothes.

The convertible bed is mounted on a frame having the end pieces A rigidly connected 45 with each other by the longitudinal bars B, and on the rear of the said ends A is pivoted at C the main top section D, adapted to rest near its front end on pins E held on the front of the ends A, as plainly shown in Figs. 2, 3 50 and 4. On the front end of the main top section D of the bed is pivoted a side section F adapted to hang down on the front of the bed, as shown in Figs. 1, 2 and 3, or adapted to be 55 swung upward into horizontal alinement with the main section D, to form a front extension for the same, as indicated in Fig. 4,

the said extension F being provided with suitable foldable legs F', braces F² and an operating device F³ for swinging the legs F' into an active or into an inactive folding position. 60 When the legs F' are moved into an active position they serve to support the section F in a horizontal position, as indicated in Fig. 4.

On the rear end of the main top section D is pivoted a rear side extension section G provided with legs G', braces G² and operating means G³ for swinging the legs G' into an active or into an inactive folding position. When the legs G' are extended they serve to support the section G in a horizontal position in alinement with the main top section D, as indicated in Figs. 2 and 4. The rear section G is also adapted to be swung upward into an approximately vertical position to form the back of a davenport, as illustrated 70 in Fig. 1, and the said side section G is adapted to be swung downward at the rear of the bed, as illustrated in Fig. 3, whenever it is desired to convert the bed into a couch. In order to lock the rear section G in the upright position shown in Fig. 1, use is made of braces G¹ pivoted on the ends of the main section D and connected by removable bolts G⁵ with the ends of the rear section G, as shown in Figs. 1 and 5. Now when the 80 bolts G⁵ are removed the rear section G can be swung down into a horizontal position, as shown in Figs. 2 and 4, or into a drop down position, as shown in Fig. 3.

The construction of the legs F', G' and 90 their operating means F³, G³ is well known so that further description of the same is not deemed necessary.

The mattress used with this convertible bed consists of a main section H and extension sections H', H², of which the extension section H' is hingedly connected at the top to the top of the main section H at one side thereof, as shown at H³, and the extension sections H', H² are hingedly connected with 100 each other at H⁴ at the bottom of the same, as plainly indicated in the drawings. Now the main section H corresponds to the main top section D of the bed in width and length, and the mattress sections H' and H² correspond in length and width approximately to 105 the section G, and the aggregate width of the sections H' and H² is approximately that of the main section H. Now by arranging the mattress in the manner described, the section H covers the main section D of the bed at the time the latter is either a davenport, 110

as shown in Fig. 1, a single bed, as shown in Fig. 2, or a couch, as shown in Fig. 3, while the section H' fits the section G at the time the bed is used as a davenport, as indicated 5 in Fig. 1, or when used as a single bed as shown in Fig. 2. The mattress section H² hangs down at the back of the davenport, as shown in Fig. 1; or down at the back of the single bed, as illustrated in Fig. 2; but when 10 the bed is converted into a couch the sections H' and H² are folded upon the main section H, as indicated in Fig. 3. When the bed is used as a double bed, as illustrated in Fig. 4, then the sections H, H', H² are disposed in a 15 horizontal position, and the section H extends over the front bed section F and partly over the main section D, and the section H' fills the remainder of the main section D, and the section H² covers the rear bed section G. 20 Thus from the foregoing it will be seen that the mattress in its different sections is so arranged relative to the sections of the bed, that in whatever form the bed is converted the mattress fits the corresponding parts, 25 thus requiring no extra or separate mattresses when converting the bed from one form into another.

In order to allow of conveniently storing the bed clothes and the like when not in use, 30 a fabric receptacle I is used, attached at its upper side edges to the longitudinal bars B by loops J, and the receptacle I is also provided at its lower corners with tying bands K adapted to be tied to the vertical posts of 35 the ends A, as plainly indicated in the drawings. Convenient access is had to this receptacle I for placing the bed clothes therein and removing the same therefrom, on swinging the main section D and with it the sections F and G of the bed into an upward position (see Fig. 5), and by having the fabric receptacle I approximately midway between 40 the floor and the top of the bed it is evident that the bed clothes are supported free of 45 the floor and free of the top of the bed.

Previous to swinging up the main section D the front bed section F is swung up somewhat beyond a vertical position, and then the main section D with the front bed section 50 F in this position is swung upward until it reaches a nearly balanced position, as shown in Fig. 5. By this arrangement the front section F is completely out of the way of the user when placing bedding into the 55 receptacle I or removing bedding therefrom. The main section D is held in this upward balanced position by a sectional brace L connecting the section D with the end A, as plainly shown in Fig. 5.

60 Having thus described my invention, I claim as new and desire to secure by Letters Patent:

1. In combination, a bed having a main

section, side sections hinged to the main section, means for supporting said side sections 65 with their upper surfaces in the same plane with the main section, means for supporting one of said side sections vertically and at right angles to the main section, and a mattress having a main section corresponding in 70 width to the width of the main section, a side section corresponding in width to one of the side sections and hinged at its top to the main section, and a side section corresponding in width to the other side section of the 75 bed and hinged by its bottom to the side section, the aggregate width of the said sections of the bed and the mattress being equal to the width of the main sections of the bed and the mattress for the purpose set forth. 80

2. In combination, a bed having a main section, side sections hinged to the main section, means for supporting said side sections with their upper surface in the same plane with the main section, and a mattress having 85 a main section corresponding in width to the width of the main section, a side section corresponding in width to one of the side sections and hinged at its top to the main section, and a side section corresponding in 90 width to the other side section of the bed and hinged by its bottom to the side section, the aggregate width of the said sections of the bed and the mattress being equal to the width of the main sections of the bed and the 95 mattress for the purpose set forth.

3. A mattress comprising a main section and a plurality of extension sections, one of 100 said extension sections being hinged to the main section by its top, and the other of said extensions being hinged to the first named extension by its bottom, the aggregate 105 width of the extensions being equal to the width of the main section for the purpose set forth.

4. A convertible bed comprising connected ends a top mounted to swing on the said ends, means on the said ends for supporting the top in a horizontal position, means for holding the top in a raised position, front and rear extension sections pivoted on the front and rear of the said top, folding legs on the said front and rear extension sections, and braces detachably connected with the main sections and with one 115 of the extension sections, for retaining said section vertical and at right angles to the main section.

In testimony whereof I have signed my name to this specification in the presence of 120 two subscribing witnesses.
